FALLING FILM HEAT EXCHANGER

George W. Haldeman, Oak Ridge, Tenn.

Application December 5, 1945, Serial No. 632,993

3 Claims. (Cl. 261—15)

1

The present invention relates to heat exchange apparatus.

In the industrial arts, various forms of apparatus have been proposed for causing the heat interchange between hot and cold bodies of liquid or gas but most of such apparatus either takes too long to cause the necessary transfer of heat or else requires the expenditure of an abnormal amount of heating or cooling energy. The rate of heat transfer from a liquid or a gas to a liquid, or a gas, depends primarily on the contact area, the difference in temperature and the heat transfer coefficient. The unsatisfactory operation of prior forms of heat exchangers is due to a large extent to the restriction of the contact area which limits the manner in which heating or cooling effects of the two fluids are associated with one another. Most types of heat exchangers incorporate the idea of two liquids or gases separated by a wall of metal or other solid material. In the falling film type of heat exchanger the heating or cooling medium is caused to overflow the top periphery of a vertical pipe to flow by gravity down the inside wall in the form of a thin layer or a falling film of liquid. Due to the thinness of this layer, the turbulence and relatively high rates of flow considerable heat transfer coefficients are obtained. While this type of heat exchanger gives a certain amount of satisfaction, it is subject to a number of factors which greatly reduce its efficiency of operation.

One primary defect is the non-uniformity of flow of the thin liquid layer down the vertical pipe. The initial vertical velocity of the liquid as it overflows the top periphery of the pipe is zero or nearly zero and the rate down the pipe is accelerated by gravity until a steady state condition is reached at which point the average vertical velocity is constant. It is therefore apparent that the upper part of the tube or pipe, due to the lower velocities in this region, is not utilized for heat transfer at its maximum efficiency. The liquid velocity down the tube is limited to the steady state velocity caused by gravity because it is only in this direction that the liquid can flow since it takes the shortest path between the top and the bottom of the tube. In addition to the difficulties discussed immediately above, there is also the problem of even distribution of liquid around the periphery of the tube where it overflows the pipe and then moves over the interior surface of the pipe. On occasion, the upper edge of the pipe is sometimes notched to assist in distributing the liquid

2

but even this expediency is not altogether successful unless the tube be perfectly vertical and its upper edge be maintained strictly horizontal. In these prior forms of heat exchangers the quantity of liquid per unit of time which can be passed down the tube is limited. When quantities become too great, the liquid breaks loose from the pipe wall where it overflows since the liquid must change direction at this point. This results in liquid falling free down through the space in the middle of the tube or pipe, resulting in poor heat transfer and large entrainment losses if a gas is being passed through the center of the tube.

15 The primary object of the invention is to provide heat transfer apparatus which will not be subject to the difficulties set forth above and one in which greater quantities of fluids can be accommodated and the heat transfer from one fluid to another is effected at a relatively high efficiency.

Another object is to provide a heat exchanger of the so-called "falling film" type in which the movement of the liquid through the exchanger is at a much greater rate than in the earlier types of apparatus.

Still another object is to provide a heat exchanger which is of inexpensive design, easy to assemble and operate and one which will handle considerable quantities of fluids per unit weight and per unit space taken by the apparatus.

As will be explained in detail, my improved device can, on account of its design, be used for other purposes than transferring heat from one medium to another and specifically, for combining liquid with gases or for forcing gases out of liquid solutions. Accordingly, another object is to provide apparatus, the primary purpose of which is to effect highly efficient interchange of heat between two adjacent but separated fluids but may also be used for efficiently dissolving gases in liquids or for removing such gases from the liquids at room or elevated temperatures.

45 By reason of its efficient heating effects or rather the transfer of heat from one medium to another, my improved apparatus lends itself readily to a rapid concentration of mixtures or colloidal compositions.

50 The above objects can be attained in brief by providing a jacketed cylinder and admitting one of the fluids under pressure into the cylinder in such a way that the fluid is caused to closely hug the interior surface of the cylinder and to take a spiral path through the device as a thin layer so

that the contained heat can be readily transferred through the wall of the cylinder to the fluid in the jacket. Inasmuch as the liquid is caused to be localized or concentrated around the interior wall of the cylinder leaving an open core down through the middle, a column of gas can be caused to flow through this core and if desired closely to intermingle with the liquid layer. Thus, the liquid is distributed over a wide area determined by the interior surface of the container and the thickness of the layer is substantially uniform throughout the area so that the rate of travel of the liquid through its spiral path is substantially uniform throughout the length of the cylinder.

Other objects and features will be apparent as the specification is perused in connection with the accompanying drawings, in which:

Figure 1 represents a vertical cross-section of the improved heat exchanger.

Figures 2, 3 and 4 are sectional views taken along lines 2—2, 3—3 and 4—4, respectively, in Fig. 1 and looking in the direction of the arrows.

Figure 5 is a vertical sectional view of a modified form of heat exchanger, while Fig. 6 is a transverse sectional view taken along line 6—6 in Fig. 5.

Figure 7 is a fragmentary sectional view of still another modified type of the improved heat exchanger and Figure 8 is a transverse sectional view taken along line 8—8 in Figure 7, the pipe and boss being omitted in this figure.

Referring more particularly to Figures 1 to 4, numeral 1 designates a casing, preferably of cylindrical configuration and made of any suitable metal such as cast iron and depending on the character of the fluids passing through the apparatus. The casing 1 contains an annularly arranged cylinder 2 preferably formed integral with the casing by a casting process.

The inner cylinder 2 is flared outwardly and upwardly as indicated at 3 to join with the outer cylinder or casing 1 and the latter terminates at the top and bottom in a relatively heavy cylindrical portion 4. The lower portion 4 may have integrally joined thereto a plate 5. It is evident that the elements 1, 2, 4 and 5 may conveniently be formed by casting and the annular opening 6 between the walls 1, 2 obtained through a coring operation. The casing 1 is provided at the upper end with a boss 7 which contains a threaded opening for receiving a pipe 8. At the lower end of the casing, there is a tangentially extending projection 9 (Fig. 4) which receives a pipe 9a leading through a conduit to a source 9c of heated or cooled fluid. It is apparent that the opening in the boss 7 and the opening 9d in the pipe 9a should be sufficiently large through which to remove the sand core which forms the annular space 6 in the casting operation. The heated or cooled fluid in the reservoir 9c is maintained under sufficient pressure in any suitable and well known manner to cause an upward flow of the fluid through the jacket or compartment 6 in a spiral path due to the tangential position of the opening 9d.

The end of the upper casing portion 4 is also provided with a tangentially extending projection 10 containing an opening which is threaded to receive a pipe 11 (Fig. 2). The extreme end of the lower casing portion 4 is provided with a round boss 12 which has a threaded opening to receive a pipe 13.

The upper end of the casing is closed by a plate 14 which sets on the portion 4 preferably by

means of an annular recess and is secured to the casing by screws 15 or in any other suitable manner. The closure plate has a downwardly extending centrally disposed tube 16, preferably hollow at its interior, as indicated at 17, for reasons which will be explained presently and the upper end of the opening is threaded to receive a plug 18. The tube 16 extends into the compartment 18' formed by the inner cylinder 2 for an appreciable distance. This tube preferably has an outside diameter slightly less than the interior diameter of the cylinder 2 so as to permit a thin layer of liquid or gas to pass therebetween as will be explained presently. A conduit 19 is connected with the pipe 11 in communication with a pump 20 of any suitable type. The opposite or suction side of the pump is taken from a source of fluid or liquid (not shown) which it is desired to heat, or to cool, by passing through the heat exchanger.

In order to reduce friction and eddy current loss as much as possible, it is preferred that all the corners be rounded by the use of fillets or gradual curves and surfaces of this character are readily obtainable by properly shaping the casting patterns and the cores. As shown, the wall 3 is preferably of a spherical shape in order to facilitate the ready movement of the fluid.

In operation, heated fluid from the reservoir (not shown) is caused by the pump 20 to enter the space 23 at the upper end of the casing through the tangentially positioned opening 10. This fluid completely fills space 23 and is caused to move downwardly through the casting in a spiral path due to the acquired tangential or centrifugal velocity and the composite effect of gravity so that a layer 24 of fluid emerges from the annular space between 2 and 16 along the interior surface of cylinder 2 beginning at the bottom of tube 16. The thickness of this layer is dependent on many factors including the quantity of the fluid which is caused to pass through the casing and the amount of space between the elements 2 and 16. Its rate of movement, disregarding the downward pull of gravity, is, in general, dependent on the pressure at which the fluid is introduced into the upper portion 4. This pressure and the velocity obtained thereby should be such that all of the fluid is caused tightly to hug the interior surface of the casing throughout its length so that the layer will represent an unbroken body of fluid travelling around the casing and in a constantly downward direction. This spiral movement of the fluid has been broadly indicated by the arrows 25, 26. Due to the presence of higher velocities at the top of the casing the angle of travel of the fluid at this point would be considerably less than at positions farther down the casing, and this change in angle has been indicated on the drawings by the changing distances between the spiral loops. For optimum results, although not necessary, the spiral angle should be approximately 30° at the top of the inner casing 3 and not more than 60° at the lower end of that casing. The fluid eventually reaches the lower casing portion 4, as indicated at 27, and is withdrawn at the pipe 13, either by a pump or solely by gravity effects.

It is apparent that the centrally disposed tube 16 serves to enhance the initiation of the spiral movement given to the fluid at the top of the casing in that it prevents any undue turbulence at this point and constrains the fluid to take a circular path before emerging through the annular space as a film of fluid.

Due to the fact that the fluid, in moving through the spiral path, closely hugs the interior surface of the casing 2 but more especially due to the continuity of the layer, the heat transfer coefficient at the wall 2 is relatively high. The thermal resistances of the laminar layer becomes low and the rate at which the liquid passes by the metal wall is essentially increased. The initial velocity of the liquid emerging through the annular space between cylinder 2 and tube 16 is even greater than the steady state velocity since it is dependent primarily on the pressure of the entering liquid, although eventually if the tube were long enough, the steady state velocity would be reached in normal lengths and average velocity would be obtained greatly in excess of the steady state velocity. In addition, the liquid in travelling the spiral path, has a rotary velocity that greatly increases the net velocity. Conversely, the liquid travels through a much greater distance in reaching the lower end of the tube. Approximately 5 to 10 times as much liquid can be passed down the inside wall with the improved type of heat exchanger. The centrifugal force caused by the rotary motion forces the liquid against the tube wall and if a part of the liquid breaks away from the tube wall, it will be thrown back into the stream, thus insuring good control of the liquid at all times.

Thus, as the fluid in the central compartment is caused to flow in the manner described and assuming that the fluid is at higher temperature than the fluid in the annular compartment 6, the circularly moving fluid is caused readily to give up its excess heat to the surrounding column of fluid. The fluid in this column is kept at a lower temperature than the fluid in the central compartment by a continual movement of the fluid through the compartment 6 from the reservoir 9c. It is apparent that the reverse operation takes place in the event that the fluid passing through the central compartment is at a lower temperature than the fluid in the annular compartment because the central compartment fluid would abstract heat from the adjacent column of fluid through the action of the falling layer 24.

The tangential manner in which the outer column of fluid is caused to enter the casing 1 at the pipe 9a reduces turbulence which in turn causes some increase in the velocity of the fluid moving through the casing. It will be understood that, if desired, the fluid in casing 1 could be introduced through a diametral connection, rather than tangential. Accordingly, my improved thin layer or falling film type of heat exchanger lends itself to all of the advantages to which prior forms of heat exchanges are adapted but to a greater degree due to the increase of the heat exchange coefficient obtainable from the device. This coefficient is greatly increased over prior heat exchangers insofar as the transfer of heat is concerned through the wall 2. It operates in both directions so that the device can be used to cool liquids or fluids quite as well as heat the same, depending on the relative temperatures of the fluid contained in the two compartments 6 and 18'.

In Figures 5 and 6, there is illustrated my improved heat exchange apparatus which has been adapted to the simultaneous treatment of gaseous as well as liquid fluids. In this case, the plug 18 of the structure shown in Fig. 1 has been removed and replaced by a threaded pipe 28 which is in communication with the interior of

the tube 16. The pipe may be conveniently held in position by means of a flange 29. The lower end of the casing is apertured to receive a relatively long centrally disposed tube 30 held in position by a flanged element 31 secured to the lower side of the plate 5. Gas of any desired kind could be introduced at the tube 28 and caused to pass downwardly through the tube 16 and the gas can be caused to be dissolved into the liquid as it falls as a layer over the interior surface of the casing 2. The excess gas may then be drawn through the pipe 30. It is apparent that the moving thin film of liquid may be caused, not only to absorb gas but also to disassociate therefrom any gas that is dissolved in the liquid and the disassociated gas can be pumped out through the pipe 30. In the latter event, the upper pipe 28 would be plugged similar to the structure shown in Fig. 1 and a suction pump would be connected with the tube 30. It is further evident that if the liquid in the central pipe 2 is heated by a surrounding body of heated fluid in the compartment 6, the disassociation of gas from the central column of liquid is facilitated. As in the case of the structure shown in Fig. 1, the device illustrated in Fig. 5 provides a highly efficient exchange of heat between the two compartments 6 and 18' so that the disassociation of the gases contained within the liquid is facilitated at these elevated temperatures.

The heat transferring fluid is introduced into the chamber 6 through a pipe 8' which is threaded in a boss 7', the fluid being placed under pressure at a reservoir 9c. The fluid moves upwardly through the chamber and leaves at the pipe 8 as was explained in connection with Fig. 1.

The casings 1 and 2 have been shown as being made separate and secured together at their ends although if desired, the elements could be cast integral as indicated in Fig. 1.

The layer formation of the liquid serves to cause ready absorption of the gas if the latter were maintained under considerable pressure. Other advantageous results may be obtained by admitting the gas through the tube 30 and exhausting the same from the tube 28, thus causing the gas to move through the central container in a direction opposite the downward spiral movement of the liquid. In some cases, it may even be desirable to have the middle portion evacuated of gas and operated under a partial vacuum. In fact, the versatility or adaptability of the device is practically limitless as to the various combinations of fluids, gas and liquid, that may be employed in each of the compartments 6 and 18', and the manner in which such fluids are introduced.

The primary feature or consideration in all of these uses or adaptations is the fact that the liquid is caused to spread out over large areas in the form of a relatively thin but thoroughly continuous layer which offers the greatest exposure both to the wall 2 and also to any gases contained within the wall.

Figures 7 and 8 show still further modifications which are based, for the most part, on the structure as illustrated in Figure 1 except that the plug 18 is provided with an opening which tightly receives a pipe 32, bent at the lower end, as indicated at 33, and is directed toward the interior surface of the wall 2. The tangentially extending projection 10 containing an opening which receives the pipe 11 as was explained in connection with Figs. 1 and 2, is also employed in Figs. 7

and 8. When gas under pressure is forced through the pipe 32 from a source (not shown), the gas column is caused to rotate around the interior surface of the wall 2 and also to move downwardly over the wall in a spiral path. Thus, the gas is caused to strike the liquid layer which is also travelling through a spiral path at many areas, causing the liquid to absorb or in some other manner to react with the gas during the downward travel and particularly, if the liquid is maintained at an elevated temperature.

From the foregoing, it is evident that I have disclosed an improved form of heat exchanger in which the velocity is increased by spiraling the liquid so that the average net liquid velocity is much greater than can be obtained with conventional "falling film" heat exchangers. These high net liquid velocities result in exceptionally high heat transfer rates. The turbulence in the liquid layer next to the tube wall is also increased and this increase of turbulence enhances still further the heat transfer effect which is obtained at the higher liquid velocities. The spiral motion and the use of a chamber leading into an annulus results in good distribution of liquid around the periphery of the tube, and in addition, the centrifugal force exerted at all sections of the tube results in a uniform thickness of the liquid layer. When gas is admitted to the tube, the spiral motion prevents small droplets of liquid from breaking away from the liquid layer and entering the gas stream. Any such droplets that do leave the liquid are immediately thrown back into the layer due to the spiral motion of the liquid. The heat exchanger is unique in that it provides a liquid surface at the same time the heating or cooling takes place. This surface allows other operations to take place simultaneously. The most common operation would be evaporation from the liquid surface. By operating the liquid close to the boiling point, this evaporation could be used for rapid concentration of the liquid.

I am aware that the invention may be embodied in other specific forms without departing from the spirit or essential attributes thereof, and I therefore desire the present embodiment to be considered in all respects as illustrative, and not restrictive; reference being had to the appended claims rather than to the foregoing description to indicate the scope of the invention.

Having thus fully described my invention, what I claim as new and desire to secure by Letters Patent, is:

1. Heat exchange apparatus comprising a hollow cylindrical container terminating in portions of enlarged diameter, a cylindrical jacket secured to the end portions of the container to leave an annular space between the intermediate portion of the container and the jacket, a tangential port in one of said enlarged portions of the container to admit fluid and to provide a whirling action thereof within the said container portion, a cylindrical tube having a diameter slightly less than the size of the intermediate portion of the container to leave an annular space between the tube and said intermediate portion of the container, whereby the whirling fluid as it leaves said annular space is confined as a layer against the container, inlet and outlet ports at opposite ends of

said jacket for introducing liquid in heat transferring relation with respect to the liquid in said container.

2. Heat exchange apparatus comprising a hollow cylindrical container terminating in portions of enlarged diameter, a cylindrical jacket secured to the end portions of the container to leave an annular space between the intermediate portion of the container and the jacket, a tangential port in one of said enlarged portions of the container to admit fluid and to provide a whirling action thereof within the said container portion, a cylindrical tube having a diameter slightly less than the size of the intermediate portion of the container to leave an annular space between the tube and said intermediate portion of the container, whereby the whirling fluid as it leaves said annular space is confined as a layer against the container, an inlet port in said jacket at the end of the apparatus opposite from said tangential port and tube, an outlet port in said jacket at the end of the apparatus adjacent said tangential port and tube, and means for maintaining the interior of the jacket full of liquid and to cause the liquid to move in a direction opposite from the direction in which the fluid layer moves through said container.

3. Heat exchange apparatus comprising a hollow cylindrical container terminating in portions of enlarged diameter, a cylindrical jacket secured to the end portions of the container to leave an annular space between the intermediate portion of the container and the jacket, a tangential port in one of said enlarged portions of the container to admit fluid and to provide a whirling action thereof within the said container portion, a cylindrical tube having a diameter slightly less than the size of the intermediate portion of the container to leave an annular space between the tube and said intermediate portion of the container, whereby the whirling fluid as it leaves said annular space is confined as a layer against the container, inlet and outlet ports at opposite ends of said jacket for introducing liquid in heat transferring relation with respect to the liquid in said container, means for introducing gas into said tube to cause the gas to intermix with the fluid as it flows through the container in the form of a whirling layer, and a pipe extending into the container at the end opposite from said gas introducing means for carrying away the gas which remains free of said fluid.
